PLASTIC MATERIAL MIXING DEVICE

Allen L. Stone, San Francisco, Calif., assignor, by
mesne assignments, to Pneumastic Co., Inc., a
corporation of Nevada

Application April 20, 1938, Serial No. 203,077

13 Claims. (Cl. 259—151)

This invention relates to a device for mixing plastic materials in which the various ingredients such as water, sand and cement are conveyed by air pressure to a tortuous mixing chamber in which a thorough mixing action is performed by virtue of the construction of the chamber and the air pressure so that a continuous mixing operation can be performed and the mixed material delivered from the chamber by the air pressure.

In known mixing apparatus using compressed air, all of the granular ingredients, such as sand and cement, are pre-mixed and must be dry for this purpose at the time they are used and are delivered under air pressure to a nozzle where they are mixed with a jet of water immediately before delivery of the mixture in the form of a spray from the nozzle. This method is disadvantageous because to obtain thorough mixing of the cement and sand in the proper proportions the sand must be entirely dry and the mixture must be kept dry until it is used. In addition, for most applications it is undesirable that the mixture be delivered in the form of a spray, as it cannot be used for some kinds of work. As a result, the use of this type of apparatus has been limited.

I have discovered that an efficient mixing operation can be performed with substantially all plastic materials of the character referred to, by conveying the cement or similar bonding material separately in a dry state to a mixing chamber of special construction and combining it therein with the proper proportions of sand and water, which are mixed and conveyed to the chamber together. The mixing chamber is of a portable nature so that the material can be mixed at or closely adjacent to its point of application, and remote from the supply of materials. The mixed plastic material can be obtained in substantially any desired consistency, and is discharged from the chamber by air pressure in the form of small balls or pellets of material, so that it can be used on substantially all types of jobs. The character of use will determine the type of discharge, and if desired, a spray can also be obtained by making a very thin mix and by using an appropriate nozzle.

It is a general object of the invention, therefore, to provide an improved method and device for mixing plastic materials adjacent the point of use thereof.

Another object of the invention is to provide apparatus for mixing plastic materials, in which the bonding ingredient is conveyed to the mixing

chamber in dry form for mixing with the other ingredients.

Another object of the invention is to provide a mixing chamber for plastic materials in which the materials are conveyed thru the mixing chamber by air pressure and subjected to a continuous mixing operation while travelling therethrough.

Another object of the invention is to provide mixing apparatus of the character referred to, which can be used in mixing material of a desired consistency at a point remote from the source of supply.

Other objects of the invention will appear from the following description of certain preferred embodiments thereof, as illustrated in the accompanying drawings, in which

Fig. 1 is a schematic elevational view of the mixing apparatus.

Fig. 2 is a schematic plan view of a portion of the apparatus.

Fig. 11 is a sectional elevational view of the mixing chamber taken as indicated by the line 11—11 in Fig. 10.

Fig. 12 is an end elevational view of the mixing chamber as shown in Fig. 10.

Generally, the apparatus includes sources of supply of the various ingredients including the water, sand, and cement, together with a source of air under pressure for conveying the material through hose lines to a mixing chamber of portable nature which can be located closely adjacent the point of application of the plastic material. With the mixing chamber any suitable form of applying device can be used such as a hose having an open or spray type nozzle, as desired, or a rotary trowel of the character disclosed in my

55

co-pending application Serial No. 176,922, filed November 27, 1937.

Referring to Figs. 1 and 2, there is shown a water tank 14 suitably disposed with respect to a pair of sand hoppers 15 and a pair of cement hoppers 16. The respective hoppers may be conveniently mounted for cooperative relation with an air manifold 17 which receives air under pressure from a suitable source of compressed air 18. The provision of the two sand and cement hoppers enables continuous operation of the mixer, as one pair of hoppers can be used while the other pair is being filled. Each of the sand hoppers 15 communicates with the air manifold 17 thru suitable valve means 19, which are also connected thru respective pipes 20 with water pipe 21 communicating thru valve 22 and automatic shut-off valve 23 with water tank 14. Pipes 20 and 21 provide a mixture of sand and water which is conveyed by the air pressure thru a suitable hose 24 to the mixing chamber in the gun mixer 26. Each of the cement hoppers 16 has associated therewith suitable valve means 31 in discharge pipe 32 and connected to air manifold 17, whereby cement discharged from the hopper will be picked up and carried by the air current therefrom thru flexible hose 33 which communicates with mixer 26 in a manner later described. The hopper and air manifold connections may be of conventional construction such as those now commonly employed and are not described in detail.

Preferably, valve 23 (Fig. 3) includes shell 36 having centrally disposed spider bracket 37 mounted therein to support float valve 38, which is provided with vertically disposed rod 39 slidably engaged with the bracket to guide the movement of the valve. If pressure builds up in the line when the flow of material from the mixer is shut off, the rising level of water in shell 36 will seat float valve 38 against the upper wall of shell 36 to prevent back-flow of the water and unnecessary loss of pressure in the system.

From the above description, it is seen that dry cement and a mixture of sand and water are conveyed by air pressure to the mixer 26, whose construction and operation is described hereinafter. From mixer 26 the mixed plastic material may be discharged into a flexible hose 41 (Figs. 1 and 4) from which it is used as desired, either directly from the hose for some operations, such as grouting or filling forms, or through a plastic material applying tool, such as rotary trowel 42, generally of the character disclosed in said application.

Generally, the tool 42 (Fig. 4) comprises a central material supply tube or conduit 43 mounted centrally in split casing 44, and a material applying bell-shaped rotor 46 journaled by suitable bearing means (not shown) on tube 43 and having respective seals 47, 48 and 49 with tube 43 and casing 44. Rotor 46 carries annular surface engaging planing blade 51 and rotary mixing and trowelling blade 52 which operate to locate the tool and control the application of the material to the surface. Thus far the tool construction described is similar to the disclosure in said application.

Preferably, rotor 46 (Fig. 1) is driven from the source of compressed air 18 and for this purpose is connected thereto by flexible air hose 53 (Figs. 1 and 4) which is connected by nozzle fitting 54 (Fig. 4) with casing 44 to direct an air jet against blades 56 of air wheel 51 secured to rotor 46 to supply the drive therefor. Air pressure release apertures 58 are provided in both casing 44 and rotor 46. In operation, the plastic ma-

terial fed through tube 43 is received by trowel 52 and worked outwardly to the surface engaged by the planing blade 51, the material being applied thereto in an even manner by the combined action of the trowel 52 and the blade 51.

The mixer comprises generally a tortuous or zigzag chamber formed of resilient material, such as soft rubber, and having alternate enlargements and restrictions so that the material laden air stream will alternately be expanded and compressed while changing its direction of movement as it follows the zigzag passage so as to repeatedly strike and rebound from the resilient walls defining the passage. The respective dry and moist material discharge outlets cause such material to impinge on a resilient wall at the feed end of the passage and are thereafter carried through the chamber while being thoroughly mixed.

In the form of the invention shown in Figs. 5-9, the mixer comprises metal cylinder or casing 61 having clamp rings 62 threadedly engaged over the ends thereof in radially overlapping relation with feed end plate 63 and discharge end plate 64, respectively. Compressed between end plates 63 and 64 are a plurality of chamber forming resilient segments of rubber or the like including feed end segment 66, interchangeable intermediate segments 67 and discharge end segment 68. The segments are all formed to fit within casing 61 and to provide air pockets 71 therewith and to provide a tortuous or zigzag mixing passage between the mating faces of the segments.

Feed end segment 66 (Fig. 5) forms with the adjacent intermediate segment 67 an enlarged chamber 72, into which open respective conduits 73 and 74 formed integrally with end plates 63 and having respective valve connections 75 and 76 with hoses 33 and 24 respectively. Conduits 73 and 74 are directed to cause the material ejected therefrom to impinge against wall 71 of chamber 72, the conduit 73 opening through self-closing nipple-type nozzle 78 (Figs. 5 and 9) formed integrally in segment 66 by having its end wall slotted in two planes at right angles to form nipple segments 79. This construction provides for free passage of material outwardly from conduit 73, but is self-sealing when the pressure in chamber 72 exceeds that in conduit 73 to prevent any moisture from entering the conduit.

Intermediate segments 67 (Figs. 5, 7, and 8) are interchangeable and have their facing sides recessed to form successive enlargements or chambers 81 in the straight sections of the passage and to form restrictions or necks 82 (Figs. 5-8) between the chambers 81. As seen in Figs. 7 and 8, the chambers 81 are of substantially circular outline in one cross-sectional direction and in the other are substantially rectangular and have a depth substantially equal to the diameter of necks 82. In this manner, the successive enlargements and restrictions of the passage are in a direction at right angles to the direction of the zigzag path of travel provided therethrough, to provide for the desired rebound and changed direction of the particles of material in travelling through the passage.

Discharge end segment 68 has restricted discharge passage 86 leading to conduit 87 formed integrally with plate 64, and the segment 68 is also formed with air pocket 88 adjacent the chamber 81 formed thereby.

It will be understood that the number of intermediate segments 67 and the length of cylin- 75

der 61 may be selected in accordance with the character of mixed material which is desired, and the required time of the mixing action.

In the form of the invention shown in Figs. 10 and 11, the construction will be described only insofar as it differs from that shown in Figs. 5-9. Casing 61 receives integrally formed passage member 91 of resilient material compressed between end plates 63 and 64 and secured to respective conduits 13, 14 and 87 by respective clamps 92. End plates 63 and 64 are held in place by clamp rings 93 and a plurality of tie rods 94 extending therebetween.

Resilient member 91 (Figs. 10 and 11) is provided with a longitudinally extending material mixing passage formed in zigzag fashion with alternate enlarged chambers 81 and necks 82 leading from the feed chamber 72 into which respective feed passages 73 and 74 discharge. Passage member 91 is supported at spaced points by the casing 61 so as to provide air pockets 71 similar to the construction of Figs. 5-9.

Preferably, means is provided for adjusting the depth of the passage means to provide an adjustable restriction therein. For this purpose, leaf spring 96 (Fig. 10) is carried on the reduced end of adjusting screw 97 threadedly engaged with collar 98 secured in casing 11. The ends of leaf spring 96 engage flat walls of adjacent chambers 81 and when the spring is adjusted inwardly, serve to produce an additional restriction in the respective chambers.

The operation of the mixing device is similar for both forms and will be described with reference to the construction shown in Figs. 5-9, and with reference to the mixing of cement, sand and water.

As previously stated, dry cement is discharged through nozzle 18 and a mixture of water and sand is discharged from conduit 74, both under pressure and carried by respective air streams, to strike against resilient wall 71 from which they rebound toward the upper wall of chamber 72 so as to produce a whirling motion therein to perform the first mixing operation, during which an expansion takes place. From chamber 72, the mixture of cement, sand and water passes through the first restriction 82, where the pressure increases and into the adjacent enlarged chamber 81 where a second expansion occurs, this operation being repeated until the mixed material is discharged through conduit 87.

As the material moves through the zigzag passage, it rebounds back and forth between the "live" rubber walls, and the individual particles have their direction of movement changed repeatedly both by the zigzag path of travel and the alternate expansion and contraction afforded by the successive enlargements and restrictions of the passage. This results in a thorough mixing action, so that the material is discharged in uniform condition from the discharge outlet.

Because the cross-sectional area of the restrictions 82 is less than the combined cross-sectional areas of the inlet passages through conduits 73 and 74, the material tends to build up in volume as it progresses through the passage, and is delivered from the conduit 87 in successive masses or pellets as the material fills the passage so as to be discharged by the air pressure. As pointed out, the mixed material may be delivered from discharge conduit by means of a hose alone, or to a plastering device of the character shown.

It will be noted that the resilient construction 75 of the passage walls will effect a continuous vi-

bration thereof during operation to prevent caking of the material, and to enable easy cleaning of the passage after use of the mixing device.

The length of the passage is determined by the character of materials being mixed, the use for which it is intended, and the desired constituency. A shorter passage is employed for thinner mixes, and also where considerable discharge force is desired, as for cement walls and filling of rock pockets, beams, columns and the like. For delivery to a mortar board or a plastering machine, where a small discharge pressure is desirable, a longer passage may be employed. In the form of the invention shown in Fig. 5, the change in length of the passage can be effected by using the desired number of intermediate sections 87, with the proper length casing, while in the form shown in Fig. 10, different sizes are built to meet different requirements.

It will be understood that my device can be used successfully in mixing all types of plastic materials commonly used in building construction. While I have shown and described certain preferred embodiments, the invention is capable of both variation and modification from the form shown, and, therefore, its scope is to be limited only by the scope of the claims appended hereto.

I, therefore, claim as my invention:

1. A plastic material mixing device comprising a resilient body having a feed chamber adjacent one end thereof and a zigzag passage leading from said feed chamber, and having a restriction therein, and a pair of feed passages opening into said feed chamber and positioned to direct the material discharged therefrom against a resilient wall of said chamber, the combined cross-sectional area of said feed passages being greater than the cross-sectional area of said restriction.

2. A plastic material mixing device comprising a resilient body having a feed chamber adjacent one end thereof and a tortuous passage leading from said feed chamber, the resilient walls defining said passage alternately receding from and approaching each other to provide alternate restrictions and enlargements in said passage, and means providing air pockets adjacent the enlargements of said passage.

3. A plastic material mixing device, comprising a casing, a resilient body mounted in said casing and supported thereby at spaced points to provide air pockets therebetween, and zigzag passage means extending through said body.

4. A plastic material mixing device, comprising a casing, a resilient body mounted in said casing and supported thereby at spaced points to provide air pockets therebetween, zigzag passage means extending through said body, and spring means mounted in said casing for adjustable engagement with said body to vary the cross-sectional area of said passage means.

5. A plastic material mixing device, comprising a casing, a resilient body mounted in said casing and supported thereby at spaced points to provide air pockets therebetween, and zigzag passage means extending through said body, the resilient walls defining said passage means alternately receding from and approaching each other to provide alternate restrictions and enlargements in said passage means.

6. A plastic material mixing device, comprising a casing, a resilient body mounted in said casing and supported thereby at spaced points to provide air pockets therebetween, and tortuous passage means extending through said body and

having its discharge means of smaller size than its feed means.

7. A plastic material mixing device, comprising a casing, a resilient body mounted in said casing and supported thereby at spaced points to provide air pockets therebetween, and tortuous passage means extending through said body and having its discharge means of smaller size than its feed means, the resilient walls defining said passage means alternately receding from and approaching each other to provide alternate restrictions and enlargements in said passage means.

8. A plastic material mixing device, comprising a longitudinally extending casing, end plates adjustably connected to said casing, a resilient body mounted in said casing and compressed between said end plates, a feed chamber adjacent one end of said body, a tortuous passage leading through said body from said feed chamber, and means providing spaced air pockets adjacent said passage between said casing and said body.

9. A plastic material mixing device, comprising zigzag passage means having resilient walls, the passage formed within said walls having its dimension in one transverse direction substantially constant and having its dimension in another transverse direction successively increased and decreased to provide alternate restriction and enlargements of said passage, said restrictions being located at the bends of said zigzag passage, and means providing air pockets adjacent said enlargements.

10. A plastic material mixing device, comprising a tubular casing, a resilient body mounted in said casing having zigzag passage means ex-

tending therethrough, said body being supported at spaced points only by said casing with the bends of said passage coinciding with said spaced points, the passage formed within said walls having its dimension in one transverse direction substantially constant and having its dimension in another transverse direction successively increased and decreased to provide alternate restrictions and enlargements of said passage, said restrictions being located at the bends of said zigzag passage.

11. A plastic material mixing device, comprising a tubular casing, a resilient body mounted in said casing having a zigzag outer contour to engage said casing at spaced points only, and zigzag passage means extending through said body, the walls of said passage means alternately receding from and approaching each other to provide alternate restrictions and enlargements in the passage.

12. A plastic material mixing device, comprising a frame, zigzag passage means in said frame having resilient walls, and adjusting means mounted in said frame and engaging a wall of said passage means for controlling the cross-sectional area of the passage.

13. A plastic material mixing device, comprising a tubular casing, a resilient body mounted in said casing having an irregular outer contour to engage said casing at spaced points only, passage means extending through said body, and means mounted in said casing for adjustable engagement with said body to vary the cross-sectional area of the passage.

ALLEN L. STONE. 35
